UNITED STATES PATENT OFFICE.

WILLIAM H. NICKERSON, OF BROOKLINE, MASSACHUSETTS.

CUSHIONED SHOE.

Application filed September 14, 1923. Serial No. 662,770.

To all whom it may concern:

Be it known that I, WILLIAM H. NICKERSON, citizen of the United States, residing at Brookline, in the county of Norfolk and State of Massachusetts, have invented new and useful Improvements in Cushioned Shoes, of which the following is a specification.

The object of this invention is to provide a shoe having between the ball-supporting portions of its inner and outer soles, a compressible elastic cushion, adapted to yieldingly support the shank portion of the insole under the ball of the wearer's foot.

I attain this object by the improved construction hereinafter described and claimed.

Of the accompanying drawings forming a part of this specification,—

Figure 1 is a bottom plan view of a shoe embodying the invention.

Figure 2 is a section on line 2—2 of

Figure 1.

Figure 3 is an enlargement of a portion of Figure 2.

Figure 4 is a side view of the ball cushion shown by Figures 1, 2 and 3.

Figure 5 is a rear edge view of the cushion shown by Figure 4.

Figure 6 is a section on line 6—6 of Figure 4.

Figure 7 is a view similar to Figure 4, showing a different form of the salient thickened rear margin of the ball cushion.

The same references indicate the same parts in all of the figures.

The outsole 12 of a shoe embodying the invention has a somewhat abrupt transverse bend 13 at the junction of its tread and shank portions, and under the ball of the wearer's foot, said bend extending from edge to edge of the outsole and being centrally offset, so that its end portions project forward from its central portion which is on the median line of the shoe bottom.

The bend 13 defines the rear extremity of the tread portion, and in this instance is curved as shown by Figure 1, although it may be of angular or other form, if desired.

The ball-supporting portion of the insole 14 bridges and is spaced from the bend 13, so that a double wedge-shaped pocket 15 is formed between the two soles, the forward portion of said pocket tapering toward the toe end while the rear portion tapers toward the heel end, as shown by Figure 2.

16 designates a cushion of compressible

rubber, by which I mean rubber as usually compounded for rubber shoe heels, although it may be otherwise compounded to form a suitably yielding and elastic support for the ball portion of the wearer's foot. Sponge rubber may be employed if desired.

The cushion 16 is suitably secured in the pocket 15, and is wedge-shaped and formed to fit only the wedge-shaped forward portion of the pocket 15. The cushion has a thickened rear margin 17, and a thin edged forward margin 18. The thickened margin is of salient form and conforms approximately to the form of the bend 13, as indicated by Figure 1. The forward margin 18 is preferably straight and intersects the ends of the rear margin, the latter being thickest at its central portion and gradually decreasing in thickness to its ends, as shown by Figure 5. The rear portion of the pocket is vacant and forms a wedge-shaped air space as shown by Figure 2.

The arrangement is such that, when the shoe is in use, the shank portion of the insole is permitted to conform to the portion of the foot bearing thereon, by reason of the fact that the cushion is free to bulge endwise into the said air space and the shank portion of the insole is free to bulge sideways or downward into the cushion and into the air space. The compressibility of the cushion is considerably greater than would be the case if the cushion were extended to fill the rear portion of the pocket 15, the thicker end portion of the cushion being free to bulge into an air space at the rear end of the cushion, so that the thickness of the cushion is freely reduceable.

Figure 7 shows a salient rear margin of angular form, suitable for use in a shoe in which the bend 13 is also angular.

The shank stiffener 19, with which the inner sole is usually provided, may bear on the rear end of the cushion 16, as indicated by Figures 2 and 3.

I claim:

A shoe comprising an outsole having a somewhat abrupt centrally offset bend at the junction of its tread and shank portions, said bend being located under the ball portion of the wearer's foot, extending from edge to edge of the sole, and imparting a salient form to the rear extremity of the tread portion, the shank portion of the outsole being inclined upward and rearward from said bend, an insole the ball-sup-

porting portion of which bridges and is spaced from said bend, the insole and outsole forming the sides of a double wedge-shaped pocket, and a resilient wedge-shaped rubber cushion filling only the forward portion of said pocket, so that a wedge-shaped air space is formed at the rear portion of the pocket which is bridged by a portion of the insole, the arrangement being such that 10 when the shoe is in use the shank portion

of the insole is permitted to conform to the corresponding portion of the foot by the endwise bulging of the cushion into said air space and by the downward bulging of the shank portion into the cushion and into the 15 air space.

In testimony whereof I have affixed my signature.

WILLIAM H. NICKERSON.
